CERVICAL SPLINT

Lance T. McBee, Paris Island, S. C.

Application July 19, 1946, Serial No. 684,703

13 Claims. (Cl. 128—87)

(Granted under the act of March 3, 1883, as amended April 30, 1928; 370 O. G. 757)

1

This invention relates to a cervical brace. More particularly, the invention is concerned with a brace for rotatably supporting the head of a patient from his body in a manner to relieve pressure on a cervical vertebra which has been fractured, and in all normal rotative positions of the head.

The present practice employed in treating a patient having a fractured vertebra is to immobilize the vertebra for proper union, by supporting the patient's head from his body by means of a relatively immovable supporting brace for splint parts which includes various adjustable head engaging and supporting members whereby the head may be positioned and immovably held in the desired supported position for most effective union of the fracture.

While in this practice, the vertebrae is immobilized for most effective union of the fracture, the head of the patient is maintained in a fixed supported position relative to his body with the result that the neck muscles are also immobilized so that they become weakened from lack of exercise and reduced circulation, such as is normally occasioned by natural pivotal movements of the head. Not only does this practice of using a rigid head supporting structure weaken the neck muscles by immobilization thereof, but, due to the patient's head being retained in a fixed supported position relative to his body, great discomfort as well as annoyance is experienced.

With such devices of the prior art it is necessary for the patient to turn his body in order to observe objects not then in direct line of his vision, and as a result it is believed that such fixed position of the head and body may also result in injury to the patient's eyes when attempting to roll and strain same in an effort to view objects without the laborious effort of turning his body and head as a unit.

A primary object of the present invention therefore is the provision of a cervical brace or splint having adjustable head engaging members for supporting a patient's head from his body in proper supported position for effecting union of a fractured cervical vertebra and which also provides for turning of the head while it is thus supported from the body whereby the neck muscles and tissue may be properly exercised and greater comfort experienced by the patient.

In most cases, however, it is desirable, when first applying the brace to provide means which may be operated to retain the head of a patient wholly immobilized for a predetermined time. Accordingly, a further object of the invention is the provision of a brace of the above noted character whereby the head of a patient may be temporarily restrained against turning movements but will at all times be properly supported from

the patient's body in a desired position of adjustment.

A still further object of the invention is the provision of a cervical brace of the above noted character which includes a main support having a body engaging member, and head and chin engaging and supporting pad members, the latter being vertically adjustably supported on the body engaging member, and wherein the chin engaging pad is further adjustable toward and from the head engaging and supporting pad for accurately adapting the brace to jaws of varying shapes and sizes.

Other objects and advantages of the invention will become apparent in the course of the following detailed description, taken in connection with the accompanying drawings, wherein—

Figure 1 is a perspective view of the improved brace as observed from the front of a patient wearing same;

Fig. 2 is a perspective view similar to Fig. 1 but illustrating the action of the brace in permitting the patient to turn his head while maintaining proper support of the head in all relative positions thereof, thus relieving pressure on the vertical vertebrae;

Fig. 3 is a perspective view of the brace as observed substantially from the rear of a patient wearing same;

Fig. 4 is a partial top plan view of the rotary upper part of the head supporting ring, on a substantially enlarged scale and particularly illustrating the adjustable connection of the chin supporting member therewith;

Fig. 5 is an enlarged vertical section in the plane of line 5—5, Fig. 4;

Fig. 6 is an enlarged vertical section in the plane of line 6—6, Fig. 4;

Fig. 7 is an enlarged vertical section in the plane of line 7—7, Fig. 4.

Referring now in detail to the drawings, 10 designates a body engageable harness which may conveniently comprise a fibrous breast engaging pad 11, and a similar back engaging pad 12, which pads adjustably overlap adjacent the shoulders as is indicated in Fig. 3. These pads may be constructed of any desired material and they preferably each include a relatively heavy fabric or leather facing portion 13 and 14 respectively. Straps 17 are carried by the back facing portion 14 and are provided with buckles 18 for receiving the perforated ends of straps 19 carried by the front portion 13.

A thin sheet metal plate 20 is mounted upon and secured as by rivets 21 to the front facing portion 13 and a similar sheet metal plate 22 is secured as by rivets 23 to the rear facing portion 14.

A rigid metallic ring member 25 is supported in 60 a normally horizontal plane from and above the

sheet metal plates 20 and 22 by means of tubular rod 26, whose lower ends are suitably shaped and secured as by rivets to the plates 20 and 22. The upper ends of the tubular rods are rigidly secured in any desired manner to the lower face of the ring 25, so as to extend substantially vertically from the body supported plates 20 and 22 and in turn support the said ring in the desired horizontal position from the patient's body.

A similar second ring 27 is disposed immediately above the ring 25 for rotation thereon and for this purpose the opposed adjacent faces of the rings are provided with cooperating ball bearing raceways 28 and 29 respectively. A plurality of ball bearings 30 operate in the raceways and are maintained in proper spaced relation by means of a spacer ring 31, as is common in thrust bearings. The ring 27 is also in a normally substantially horizontal plane which intersects the normally substantially vertical axis of the neck of the wearer, i. e., when the wearer is in upright position, and is rotatably supported by the ring 25 and rods 26 mounted on the upper torso engaging plates 20 and 22.

A pair of bearing ring retaining members 32 are provided in substantially diametrical relation on the ring 27 and embrace the ring 25 to prevent separation thereof. As indicated in Fig. 6 these members extend over the upper race of ring 27, along opposite side faces of both rings and may terminate slightly inwardly at opposite sides of the lower ring 25, but in spaced relation therewith. The retaining members are secured to ring 27 by means of screw bolts 32'. One of such retaining members, however, supports a screw 33 beneath the ring 25 for a purpose later to appear, and this retaining member preferably extends across the lower face of ring 25, as is indicated in Fig. 6.

The improved brace support as described further comprises means for supporting the head of the patient. This latter support is mounted directly upon the ring 27 and such means includes as one element a thin and relatively inflexible sheet metal plate 35 curved to fit the back of the head and carrying on its inner surface a suitably shaped lining pad 36. This pad is preferably V-shaped for engaging under the back of the head, as is more clearly indicated in Fig. 3. The opposite ends of the plate 35 are adjustably connected, as by straps 37, to opposite sides of a chin engaging and supporting member 38, which latter member also preferably includes a sheet metal plate, not shown, and an enclosing padding and cover.

The rear head engaging and supporting plate 35 is in turn supported from the upper face of the ring 27, by means of vertically adjustable rods including a pair of tubular sections 39, and the chin engaging member 38 is supported from a diametrical upper face portion of the same ring 27, by means of similar vertically adjustable rods 40. The rods 40 are also mounted for horizontal adjustment on the ring 27 for varying the distance between the head engaging plate 35 and the chin engaging member 38, for conforming with varying head sizes and shapes of different patients, by which means the said supporting rods 40 remain in substantially vertical positions in all positions of adjustment. Primarily, this means providing horizontal adjustment of the chin supporting pad 38, permits ease in placing and removing the cervical brace over the patient's head as the entire chain supporting assembly is easily and quickly

removed from the upper ring as will be fully understood from the following description:

For this purpose a rigid bar 41 extends across the upper face of ring 27, adjacent the front 5 thereof, and this bar is provided with a plurality of apertures 42 adjacent each end thereof. These apertures are so spaced that one thereof adjacent each end of the bar will register with one of several threaded recesses 43 in the ring 27, in different adjusted positions of the bar relative to the front of the ring, or toward and from the rear head engaging and supporting plate 35.

A stud bolt 44 extending through each of a pair of apertures 42 in the bar and registering with the 15 selected recesses in the ring 27 are threaded into the latter for holding the bar in desired adjusted position. The head end of the stud bolt may be knurled as in Fig. 5 or provided with a wrench engaging head or screw driver receiving kerf, as 20 desired, for ease in applying and removing same. The adjustable rods 40 each include a post 45 threaded into the bar 41 and a tubular member 46, having its lower end telescoped over the post. The upper end of the tubular member freely receives a threaded rod member 47 extending from 25 and suitably secured to the chin engaging member, and a nut 48 is threaded onto the member 47 to rest on the top of the tubular member 46 and provide the desired adjustment.

The adjustable rods 39 are of the same construction as rods 40 but in this case the posts 45 are secured to the ring 27. In the use of the improved cervical brace above described, the harness 10 together with the rings 25 and 27 are 35 passed over the patient's head, after which the bar 41 and rods 39 and 40 with their respective plate 35 and chin engaging member 38 are positioned, as illustrated.

The straps 17 and 19 are properly adjusted for 40 proper body engagement of the harness 10, and the straps 37 are adjusted to maintain the plate 35 and chin engaging member 38 in proper position. The nuts 48 are thereupon turned for moving the plate 35 and chin engaging member upwardly through the threaded members 47, connected therewith for supporting the patient's head from his body, and thereby relieving pressure on the cervical vertebra.

While it may be found necessary to variably adjust 50 the several rods 39 and 40 for proper support of the head for most effective unison of a fracture in the vertebra, the head will be maintained in a generally upright position as is illustrated in the drawings.

In my adjustable, rotatable cervical brace or 55 splint just described it has been found that there is no appreciable change in the relative position of the cervical vertebrae when the head is turned to the right or left provided upward supporting 60 pressure is maintained on the head from the body supported splint members. Accordingly, the rings 25 and 27 provide for natural turning movements of the head which not only is a marked convenience to the patient but is highly essential 65 from an orthopedic standpoint for exercising the neck muscles, thereby preventing weakening thereof.

While it may not be advisable that a patient 70 suffering from a fractured cervical vertebra be permitted to turn his head at all times, provision is made for locking the rings 25 and 27 against relative rotation and, as shown, such is effected by means of the screw 33 which may be turned into tight engagement with ring 25. Since the 75 member 32 is secured to ring 27, the rings will be

locked against relative rotation and the patient's head will be held immobilized. The screw may be released when conditions warrant for exercise of the neck muscles and for contributing greater comfort to the patient.

The improved compound brace as disclosed generally comprises a frame supported by the body and a head engaging frame supported on the body-supported frame, the frames including juxtaposed rotatably slid able rings having ball bearings therebetween whereby the head engaging frame which includes adjustable head supporting members is freely rotatable on the body-supported frame.

The arrangement, including the rings 25 and 27 provides a highly stable support and due to the bearings between the rings there is substantially no resistance experienced by a patient in turning his head which is highly important in preventing sudden jerks with possible pain resulting therefrom.

It should be appreciated from the foregoing disclosure that the improved cervical brace possesses all of the advantages of similar prior constructions in properly supporting the head of a patient from his body to relieve pressure on a fractured cervical vertebra while, however, at the same time providing for turning movement of the head for exercising the neck muscles, as well as providing for greater comfort to the patient wearing the brace.

The invention described herein may be manufactured and used by or for the Government of the United States of America for governmental purposes without the payment of any royalties thereon or therefor.

Having thus disclosed my invention in accordance with a preferred embodiment thereof, what I claim and desire to secure by U. S. Letters Patent is:

1. A cervical brace comprising a pair of superposed relatively rotatable rings, a body engageable harness rigidly supported by one of said rings, and head engaging members adjustably supported by the other ring.

2. A cervical brace comprising a body engageable harness, a ring supported by and above said harness, a second ring rotatably supported on the first ring, head engaging members, and vertically adjustable means supporting said head engaging members from and above said second ring.

3. A cervical brace according to claim 2 together with means for locking said second ring against rotation relative to said first ring.

4. A cervical brace comprising a substantially horizontally disposed ring, a plate engageable with the back of the head of a patient wearing the brace, a chin engageable member, means individual to the plate and chin engageable member for vertically adjustably supporting same from the ring, and body engageable means rotatably supporting the ring.

5. A cervical brace according to claim 4 wherein in said chin engageable member supporting means is selectively engageable with circumferentially spaced points on the ring for adjustment of the ring parallel to the plane thereof for varying the spacing of the plate and chin engageable member.

6. A cervical brace comprising a body engageable harness, a substantially horizontally disposed ring supported above the harness by rods interconnecting same, a second ring rotatably supported on the first ring, two pairs of vertical

ly adjustable rods having their lower ends supported by the second ring, a head engaging plate secured to the upper ends of one pair of said adjustable rods, and a chin engaging member secured to the upper ends of the other pair of adjustable rods.

7. A cervical brace according to claim 6, wherein said rings are provided with bearing races in their adjacent sides, ball bearings disposed in said races, and means secured to one ring and substantially encompassing the other ring for maintaining the bearings in the races.

8. A cervical brace comprising a pair of superposed relatively rotatable rings, a body engageable harness supported by and below the lower ring, a head engaging member vertically adjustably supported by and above the upper ring, a bar supported on the upper face of the upper ring, a pair of vertically adjustable rods having their lower ends supported by the bar, and a chin engageable member supported by the upper ends of the rods.

9. A cervical brace according to claim 8 together with means adjustably securing said bar along the upper face of said upper ring.

10. A cervical splint comprising head support means, body engaging means and a neck encircling part supported by said body engaging means and supporting said head support means, said part consisting of congruent sections slid able with respect to each other whereby the head support means and the body engaging means may be rotated independent of each other.

11. A cervical splint comprising head support means, body engaging means and an intermediate neck receiving part supported by said body engaging means and supporting said head support means, said part comprising superposed sections disposed in parallel planes and mounted for rotary movement with respect to each other in said parallel planes, whereby the head support means and the body engaging means may be rotated independently of each other.

12. A cervical splint according to claim 11 including releasable means for locking said sections together against relative rotation.

13. A cervical brace comprising upper torso engaging means, support means mounted on said upper torso engaging means, neck receiving means mounted on the said support means for free rotary movement relatively to the said support means in a predetermined path in a plane disposed to intersect the vertical axis of the neck of the wearer when the wearer of the brace is in upright position, and head engaging and supporting means on said freely rotatable neck receiving means and rotatable therewith relatively to the said support means.
